TAPE RECORDER

Richard S. Hart, Wheaton, Ill., assignor to Minnesota
Mining and Manufacturing Company, St. Paul, Minn., a corporation of Delaware

Filed Apr. 22, 1966, Ser. No. 1,978

Term of patent 14 years

(Cl. D26—14)

FIG. 1

The bottom is plane and unornamented.

I claim:

The ornamental design for a tape recorder, substantially as shown and described.
